D7/605

European Design Patent Application No. 003847557-0001 entitled "Smart Cooler" filed Apr. 7, 2017.

(Continued)

Primary Examiner — Terry A Wallace(74) *Attorney, Agent, or Firm* — Middleton Reutlinger(57) **CLAIM**

The ornamental design for a cooler, as shown and described.

DESCRIPTION

FIG. 1 is a perspective view of a first design of a cooler; FIG. 2 is a front elevation view of the design of FIG. 1; FIG. 3 is a rear elevation view of the design of FIG. 1; FIG. 4 is a top plan view of the design of FIG. 1; FIG. 5 is a bottom plan view of the design of FIG. 1; FIG. 6 is a right side elevation view of the design of FIG. 1; and, FIG. 7 is a left side elevation view of the design of FIG. 1. The broken line disclosure represents unclaimed portions of the cooler in which the design is embodied.

1 Claim, 7 Drawing Sheets# US D887,788 S
